UNITED STATES PATENT OFFICE.

ALFRED H. HUMPHREY, OF KALAMAZOO, MICHIGAN.

DESIGN FOR A GAS-LAMP.

SPECIFICATION forming part of Design No. 36,332, dated May 19, 1903.

Application filed January 6, 1902. Serial No. 88,707. Term of patent 7 years.

To all whom it may concern:

Be it known that I, ALFRED H. HUMPHREY, a citizen of the United States, residing at the city of Kalamazoo, in the county of Kalamazoo and State of Michigan, have invented a new, original, and ornamental Design for a Gas-Lamp, of which the following is a specification.

My invention relates to a new and ornamental design for gas-lamps.

My new and ornamental design for a gas-lamp is shown in the accompanying elevation drawing; and the leading and material features thereof consist of an upright central portion A, with an ornamented upwardly-expanding cylindrical casing B, on the upper end of which is the globe C. Arranged within and

projecting above said casing are tubular parts D, grouped about said central portion and bearing mantles, while above said globe is an outwardly and downwardly flaring portion M and above this a disk-like portion N.

Having thus described my invention, what I claim as new, and desire to secure by Letters Patent, is—

The ornamental design for a gas-lamp, substantially as shown and described.

In witness whereof I have hereunto set my hand and seal in the presence of two witnesses.

ALFRED H. HUMPHREY. [L. S.]
